ATTORNEY

UNITED STATES PATENT OFFICE.

REUBEN C. NORTON, OF ROCKFORD, ILLINOIS, ASSIGNOR TO THE UNION FOUNDRY AND MACHINE COMPANY, OF SAME PLACE.

HAY-CARRIER.

SPECIFICATION forming part of Letters Patent No. 328,802, dated October 20, 1885.

Application filed February 26, 1885. Serial No. 157,152. (No model.)

To all whom it may concern:

Be it known that I, REUBEN C. NORTON, a citizen of the United States, residing in the city of Rockford, in the county of Winnebago 5 and State of Illinois, have invented a new and useful Hay-Carrier, of which the following is a specification.

This invention relates to a class of machines known as "hay-carriers," employed in connection with power-forks to unload hay from 10 wagons and deliver it in the place of deposit.

The object of this invention is to produce a reliable carrier at a small cost, capable of use in opposite directions without reversing the 15 carrier on its track-support. To this end I have designed and constructed the apparatus represented in the accompanying drawings, in which—

Figure 1 is a side elevation of a carrier embodying my invention. Fig. 2 is a lengthwise vertical central section. Fig. 3 is a transverse vertical section on dotted line X. Fig. 4 is an isometrical representation of a pivoted lever-pawl, and Fig. 5 is an isometrical 25 representation of a gravity or drop detent.

In the figures, A represents the sheave-supporting beam, having its end portions provided with vertical slots to receive the rope-sheaves B. At C are represented bracket-arms fitted 30 to the sides of the sheave-supporting beams, immediately opposite the rope-sheaves. A suitable screw-bolt is passed through the bracket-arms, the sheave-supporting beam, and rope-sheaves placed therein, and serves 35 to fix the parts securely in place, and in such a manner that the sheaves will be free to rotate on their bolt-supports within the beam.

The extreme ends of the sheave-supporting beam are provided with eye-openings D, to 40 receive the rope passed over the sheaves. The center of the sheave-supporting beam is fitted on its under face with a conic opening, E, and the upper face of the beam is provided with slots F, extending lengthwise 45 thereof, opening into the conic opening. The upper face of the sheave-supporting beam is fitted with uprising ears G, having their upper ends fitted in journal-bearing form.

At H is represented a forked lever-pawl of 50 the peculiar form shown, and is fitted with journals I, projecting from its opposite sides,

which enter the bearings in the upper ends of the ears G in a manner to oscillate therein. The construction of this pawl H and its seat are such as to permit the pawl to be placed in 55 position opposite that shown in the drawings, or in a reverse position.

At K are represented traveling wheels supported to revolve on stud-journals projecting from the inner face of the upper ends of the 60 bracket-arms. At L is represented a track-way consisting of a suitable beam to be supported in position in any suitable manner. This trackway is passed through the carriage between the bracket-arms to receive the traveling 65 wheels on its upper surface in a manner to move endwise on the beam in either direction.

At M is represented a bracket fixed to the under face of the beam constituting the track-way, and operates to engage the hook-arms of the forked lever-pawl to limit the movement of the carriage on the trackway. The bracket M, fixed to the trackway-beam, is produced in socket form, and receives a drop-detent, N, placed within the socket, limited in 70 its descent by shoulders on its sides engaging inward-projecting flanges of the socket. The construction of these parts is such that in the movement of the carriage in the direction 75 of the arrow the forked lever-pawl passing under the drop-detent will cause it to rise, or the forked lever-pawl to tip downward to pass under the drop-detent; or these joint actions of the lever-pawl and the drop-detent 80 will permit the carriage to move under the bracket until the hook-arms of the lever-pawl engage the bracket to limit the movement of the carriage, at which point the drop-detent 85 will drop between the forked arms of the lever-pawl and operate to hold the carriage 90 locked in connection with the bracket.

At P is represented a sheave supported to revolve in a suitable yoke, provided with guards and a swivel-hook at its lower end. 95 This sheave-yoke is provided with a trip-arm, R, rising from its upper end to enter the conic opening in the sheave-beam to lift the drop-detent.

At S is represented a hoisting-rope passed 100 around the sheave P and through the rope-guards. Its branches are then passed over

their respective sheaves B and eyes D in the sheave-supporting beam. The end of the rope at T is knotted to prevent its withdrawing from the eye.

5 From the foregoing it will be seen that if the free end of the rope is drawn over the sheave the sheave P and its yoke appliances will be made to rise and cause the trip-arm to enter the conic opening and lift the drop-detent, free the carriage from its connection with the bracket-stop, and permit the carriage to travel on the trackway in the direction opposite to that indicated by the arrow to carry the load of hay suspended on the swivel-hook 10 to the place of deposit, and when deposited the return movement of the carriage will again lock it to the stop-bracket in position for another operation.

It will further be seen that if the forked lever-pawl H is reversed from the position shown in the drawing the carriage will be fitted to move on the way in the direction indicated by the arrow opposite to that hereinbefore described, and by knotting the free 20 end of the rope and drawing the knotted end 25 T over the sheaves the carrier will be made to operate in the opposite direction to that hereinbefore described.

By this construction I produce a carrier

capable of use in opposite directions without reversing the carriage on the trackway.

I claim as my invention—

1. The combination, with the bracket-stop supporting a drop-detent, of the carriage and its pivoted pawl, substantially as set forth. 35

2. The combination, with the bracket-stop supporting a drop-detent, of the carriage and its pivoted lever-pawl, and a trip-arm adapted to raise said detent within the stop, substantially as set forth. 40

3. The combination, with the stop and its drop-detent arranged therein, of the carriage formed with an opening, as described, a pivoted lever-pawl, and a trip-arm adapted to project through said opening to raise the detent, substantially as set forth. 45

4. The combination, with the stop, within which is supported a drop-detent, of a carriage formed with a conic opening and supporting a lever-pawl adapted to receive the drop-detent, and a trip-arm, substantially as set forth. 50

REUBEN C. NORTON.
